(57) **CLAIM**

The ornamental design of a detachable headphone, as shown and described.

DESCRIPTION

FIG. 1 is a top front right side perspective view of a detachable headphone according to our design;

FIG. 2 is a bottom front left side perspective view of the detachable headphone shown in FIG. 1;

FIG. 3 is a bottom rear right side perspective view of the detachable headphone shown in FIG. 1;

FIG. 4 is a bottom rear left side perspective view of the detachable headphone shown in FIG. 1;

FIG. 5 is a top view of the detachable headphone shown in FIG. 1;

FIG. 6 is a front side view of the detachable headphone shown in FIG. 1;

FIG. 7 is a bottom view of the detachable headphone shown in FIG. 1;

FIG. 8 is a rear side view of the detachable headphone shown in FIG. 1;

FIG. 9 is a right top view of the detachable headphone shown in FIG. 1;

FIG. 10 is a left bottom view of the detachable headphone shown in FIG. 1; and,

FIG. 11 is close-up view of a highlighted region of the detachable headphone noted in FIG. 1 according to our design.

The dot dash broken lines encircling a portion of the detachable headphone in FIG. 1 and illustrated in the enlarged view of FIG. 11 form no part of the claimed design.

1 Claim, 10 Drawing Sheets
